UNITED STATES PATENT OFFICE.

ROBERT M. NORTON AND FRANCIES A. KERSHAW, OF KENOSHA, WISCONSIN,
ASSIGNORS TO THE STERLING CYCLE WORKS, OF CHICAGO, ILLINOIS.

DESIGN FOR A BICYCLE-FORK.

SPECIFICATION forming part of Design No. 26,519, dated January 12, 1897.

Application filed November 16, 1896. Serial No. 612,368. Term of patent 14 years.

To all whom it may concern:

Be it known that we, ROBERT M. NORTON and FRANCIES A. KERSHAW, citizens of the United States, residing at Kenosha, in the county of Kenosha and State of Wisconsin, have invented and produced a new and useful Design in a Fork for Bicycles, reference being had to the accompanying drawing, forming a part hereof.

10 In the accompanying drawing the figure is a perspective view of my design.

The leading feature of my design consists in tubular portions, oval in cross-section, provided with an enlarged continuation and 15 arched portion at its upper end, which joins the tubular portions together.

A A are the tubular portions, oval in cross-section; B, the upper enlarged U-shaped

arch portion, which forms a practical continuation of and joins the parts A A together; 20 C, a projection at the central portion of the arch portion, and D a stem projecting upwardly from the projection C, the whole presenting to the eye a harmonious and ornate figure, as shown in the accompanying drawing. 25

We claim—

The design for a fork for bicycles and other velocipedes, substantially as herein shown and described.

ROBERT M. NORTON.
FRANCIES A. KERSHAW.

Witnesses:

JAMES T. QUINN,
JOHN H. CORCORAN.
